UNITED STATES PATENT OFFICE

MARK H. MARTIN, OF BALTIMORE, MARYLAND, ASSIGNOR TO THE SYMINGTON COMPANY, OF NEW YORK, N. Y., A CORPORATION OF MARYLAND

SIDE FRAME

Application filed August 26, 1925. Serial No. 52,579.

This invention relates to side frames for railway car trucks and more particularly to an improved construction of side frames with journal boxes integrally connected at the ends thereof.

The principal object of my invention, generally considered, is the construction of side frames formed with journal boxes integrally connected at the ends thereof in such a manner as to be separate from the main truss portion of the frame.

An object of my invention is the provision of an improved side frame for railway car trucks in which journal boxes are integrally formed at the ends thereof, the web of the tension member of said frame, however, not connecting directly with the journal boxes but passing above the upper inner corner of each journal box and merging with the corresponding web of the compression member.

Another object of my invention is the construction of side frames for railway car trucks in which the compression and tension members thereof are formed generally of inverted U or channel shape in cross section with the webs of said members merging at the ends thereof without intersecting journal boxes integral with the frame, said journal boxes being connected with said members by flanges extending from said web portions.

A further object of my invention is the formation of an integral cast steel side frame with journal boxes at the ends thereof, said frame involving compression and tension members of channel or U shape in cross section with the flanges of said members merging and forming continuations one of another near the journal boxes, the webs of said members, however, not connecting directly with said journal boxes.

A still further object of my invention is the provision of cast steel side frames for railway car trucks in which the compression and tension members are generally U shape in cross section with upper webs and depending flange portions, said web portions merging together over integral journal boxes adjacent the ends of the frames with the web of the tension member departing from the

upper contour thereof near said journal boxes, whereby the flanges of said tension member are continued upwardly beyond the web portions thereof and curved to merge with the corresponding flanges of the compression member, said flanges below the web of the tension member connecting the integral boxes at the ends of the frame and said connection being additionally reinforced by substantially triangular transversely extending gusset portions.

Other objects and advantages of the invention relating to the particular arrangement and combination of the various parts, will become apparent as the description proceeds.

Referring to the drawings illustrating my invention, the scope whereof is defined by the appended claims:

Figure 1 is a fragmentary side elevation of one end of a cast side frame for railway car trucks, a portion thereof being shown in section.

Figure 2 is a plan view of that portion of the side frame shown in Figure 1.

Figure 3 is a detail cross sectional view on the line 3—3 of Figure 1.

Figure 4 is a detail cross sectional view on the line 4—4 of Figure 1.

Referring to the drawings in detail, like reference characters designating like parts, there is illustrated one end of a side frame 1 formed with a compression member 2, a tension member 3, and integral journal boxes 4. As will be understood by those skilled in the art, although only one end of the frame is illustrated, the other end thereof is similarly constructed so that a symmetrical structure is formed, intermediate portions of the tension and compression members being spaced by strut or bolster column portions in accordance with the usual practice.

The compression member 2 and tension member 3 are both preferably channel or U shape in cross section. The compression member is formed with an upper web portion 5 and depending flange portions 6, said depending flange portions being preferably provided with ribs or beading 7 along their outer lower edges. Likewise, the tension member 3 is formed with an upper web 8 and

depending flanges 9 formed with beading 10 on the inner surfaces thereof along the lower edges.

The webs 5 and 8 of the compression and tension members, respectively, are continued outwardly from the central portion of the frame and are finally merged or connected together preferably over the central portion of the journal boxes 4 along a curved portion 11. In other words, the web 5 is preferably curved downwardly over a journal box at each end thereof and the web 8 is preferably curved upwardly at the corresponding positions so that one web forms, in effect, a continuation of the other, as illustrated particularly in Figure 1. It will be noted that this merging between the webs 5 and 8 preferably occurs over the axis or center of each journal box.

It will be noted that, contrary to the usual side frame construction, the web 8 does not intersect or merge with the journal boxes 4 but rather passes outwardly and upwardly above the upper inner corner of each journal box to meet the web 5 of the compression member above the roof of each box. The depending flanges 9, however, are preferably widened adjacent the outer ends and merge with the inner side walls of each journal box, as indicated at 12. Likewise, the depending flanges 6 of the compression member 2 are preferably continued beyond the web 5 thereof and extended to merge with the roof 13 of each journal box, the outer edges thereof being preferably curved along a slope corresponding to the general direction of the end portions of the compression member to an upright position corresponding to the outer side walls of the journal boxes.

The depending flanges 6 of the compression member above the web 8 of the tension member curve downwardly and around the outer corners of the usual triangular openings 14 between the compression and tension members and finally extend downwardly and inwardly to merge with the depending flanges 9 of the tension member, at 15. Inasmuch as the flanges 6 and 9 are in line, one may be considered as a continuation of the other adjacent the journal boxes, so that the web of the tension member diverges from and extends below the upper edge or contour of said member adjacent the ends thereof, as will be apparent particularly from Figures 1 and 2 of the drawings.

For further rigidifying the connection between the compression and tension members and the journal boxes, a web or flange 16 is preferably provided over each journal box 60 extending parallel with the flanges 6 and 9 of the compression and tension members from the web 8 of the tension member to the roof 13 of each journal box. The outer edges of these webs or gussets 16 preferably slope from the connection 11 between the

webs 5 and 8 to the upper outer edge of the outer brass lug 17 along the longitudinal center line of the side frame, as shown especially in Figure 2. These webs 16 preferably extend along upright longitudinal planes substantially central with respect to the side frame.

The connection between the side frame and journal boxes are preferably additionally reinforced by laterally extending gusset portions 18 between the inner side walls of the journal boxes adjacent the upper edges thereof and the side edges of the web 8 or the upper edges of the depending flanges 9, formed as flaring extensions on the web of the tension member which curve downwardly toward the ends of the frame and merge with the roofs of the boxes. Upright triangular gussets 19 may also be provided extending laterally from the depending flange portions 6 to the roof 13 of each journal box approximately in line with the inner brass lugs 20.

It will be apparent that by virtue of the aforescribed construction, a cast side frame is provided in which the main truss portion thereof is separate from the journal boxes at each end thereof but cast integral therewith. That is, the main truss portion, or the webs 5 and 8 thereof, does not merge directly with the journal boxes but is connected thereto by the depending flanges 6 from the compression member, the depending flanges 9 from the tension member, the auxiliary web portion 16 between said depending flanges and the triangular gusset portions 18 and 19. By such a construction secondary stresses adjacent the journal boxes are decreased, the journal boxes being rigidly connected at the ends of the frame, however, by the various flanges, webs and gusset portions before described.

Having now described my invention, I claim:

1. A side frame comprising a main truss portion and journal boxes separate from said truss portion but integral with the frame and braced with respect thereto by longitudinally disposed webs intermediate the side edges of said truss portion.

2. A side frame comprising a tension member, a compression member, and integral journal boxes, said tension and compression members being formed with web and flange portions, the web portions between the flange portions merging over the journal boxes without joining therewith, the tension member web portions having continuations beyond the flange portions flaring outwardly toward the journal boxes and connected thereto, and the flange portions having their lower edges curving downwardly to provide flaring ends uniting with the boxes.

3. A side frame comprising a tension member, a compression member and journal boxes integral therewith, said tension and compres-

5 sion members being generally angular in cross section with main portions intersecting each other and not the journal boxes over said boxes, and other portions extending from said main portions and joining with the journal boxes substantially along the longitudinal center line of the frame.

6 4. A truck side frame comprising a tension member, a compression member and journal boxes at the ends of said members, said tension and compression members being generally U-shape in cross-section with the webs thereof merging adjacent the journal boxes and the flanges extending from said webs to said journal boxes, and a web disposed between said flanges and connecting the tension and compression member webs to the boxes.

7 5. A truck side frame comprising a tension member, a compression member and journal boxes at the ends of said members, said tension and compression members being generally U-shape in cross section with the web of the tension member passing above the upper inner corner of each journal box and connected to said corner by flaring extensions outwardly of the flanges thereof.

8 6. A truck side frame comprising a tension member, a compression member and journal boxes at the ends of said members, said tension and compression members being generally U shape in cross section with the web of the tension member passing above the upper inner corner of each journal box and curved to align and merge with the web of the compression member over the journal box.

9 7. A truck side frame comprising a tension member, a compression member and journal boxes at the ends of said members, said tension and compression members being generally U shape in cross section with the web of the tension member passing above the upper inner corner of each journal box, curved upwardly, aligned and merging with the corresponding end of the web of the compression member over the journal box, and flanges extending from the tension member web and joining with the journal boxes.

10 8. A truck side frame comprising a tension member, a compression member and journal boxes at the ends of said members, said tension member and compression member being inverted channel shape in cross section with the webs thereof joining with each other over the journal boxes and connected with said journal boxes by the flanges extending from said webs, the flanges of the tension member having their lower edges concavely curved to effect a widening thereof adjacent the boxes, the strength of connection being further increased by flaring the web of the tension member beyond the flanges and extending said flared portions to unit with the boxes.

9 9. A truck side frame comprising a tension member, a compression member and journal boxes at the ends of said members, said tension and compression members being channel shape in cross section with the flanges of the compression member extended to the tension member adjacent the ends thereof, and from there continued as flanges of said tension member and connected with the journal boxes, the web of the tension member being flared below the roofs of the journal boxes beyond the flanges thereof, said flared portions curving downwardly below the normal level of the web toward the ends of the frame and merging with the roofs of the boxes. 70

10 10. A truck side frame comprising a tension member, a compression member and journal boxes at the ends of said members, said tension and compression members being generally channel shape in cross section with 85 openings therebetween adjacent the outer ends thereof, the flanges of said members being curved around the outer corners of said openings and joined, with the web of the tension member extended in diagonal planes, 90 passing over the roofs of the boxes, and diverging from the upper contour thereof adjacent its ends, and means disposed between said flanges and directly connecting the web of the tension member to the boxes. 95

11 11. A truck side frame comprising a tension member, a compression member and journal boxes at the ends of said members, said tension and compression members being generally channel shape in cross section with 100 openings therebetween adjacent the outer ends thereof, the flanges of said members being curved around the outer corners of said openings and joined, with the web of the tension member extended in diagonal planes and 105 diverging from the upper contour thereof adjacent its ends, said web passing above the journal boxes, curved upwardly, and merging with the web of the compression member. 110

12 12. A truck side frame comprising a tension member, a compression member and journal boxes at the ends of said members, said tension and compression members being generally U shape in cross section with the 115 webs thereof merging adjacent the journal boxes and the flanges extending from said webs to said journal boxes, and transverse gussets extending from the sides of the tension member flanges to the adjacent portions of the journal boxes and curved downwardly to below the normal plane of the tension member web. 120

13 13. A truck side frame comprising compression and tension members, and journal boxes at the ends of said members, the compression and tension members being generally channel-shape in section with webs merging together but not with the journal boxes, adjacent said boxes, and flanges continued to 125 130

merge with said boxes, and intermediate webs between said flanges extending from said tension member to the journal boxes.

14. A truck side frame comprising compression and tension members and journal boxes at the ends of said members, the compression and tension members being generally channel shape in section with webs merging together but not with the journal boxes, adjacent said boxes, and flanges continued to merge with said boxes, and an upright web extending between the roof of each journal box and the adjacent portion of the tension member web for strengthening the connection therebetween.

15. A cast side frame for car trucks having tension and compression members, the plate of the tension member being extended at its upper end and having arcuate form and merging from the upper side of the tension member into the top transverse plate of the compression member.

16. A cast side frame for car trucks having a compression member, a tension member, a journal box, a web rising from the top of the tension member and connecting the side walls of the compression member, and a rib connecting the journal box with the top of the compression member and with said web.

17. A cast side frame for car trucks having a compression member, a tension member, a journal box, and a continuous arcuate web integrally connecting the top of the compression member with the top of the tension member in the region adjacent the journal box and spaced from the journal box, said web also integrally uniting the side flanges of the compression member.

18. A cast side frame for car trucks having a compression member, a tension member, a journal box, the tension and compression members being inverted channels having their side walls united with the journal box, and an arcuate web integrally connecting the tops of the compression and tension members and the side walls of the compression member and located in the region of the journal box and spaced from the box.

19. A cast side frame for car trucks having a journal box, a compression member, a tension member, the tension and compression members being inverted channels having their side walls united with the journal box, and an integral connection between the side walls of the compression member in the region of the journal box and extending upwardly from the end of the tension member web to the end of the compression member web.

20. A truck side frame comprising a tension member, a compression member and journal boxes at the ends of said members, said tension and compression members being generally U-shape in cross section with the web of the tension member passing above the level of the upper inner corner of each

journal box and curved to aline and merge with the web of the compression member.

21. A truck side frame comprising a tension member, a compression member and journal boxes at the ends of said members, said tension and compression members being generally U-shape in cross section with the web of the tension member passing above the level of the upper inner corner of each journal box, curved upwardly, alined and merging with the corresponding end of the web of the compression member, and flanges extending from the tension member web and joining with the journal boxes.

22. A truck frame having journal boxes at the ends thereof, said frame having top and bottom compression and tension members cast in one piece, said members being channel shaped in cross section with their webs on the upper sides thereof, the web of the tension member projecting into the space between the tops of the journal boxes and the web of the compression member and curved adjacent the latter.

23. A truck frame having journal boxes at the ends thereof, said frame having top and bottom compression and tension members cast in one piece, said members being channel shaped in cross section with their webs on the upper sides thereof, the web of the tension member having extensions integral with the side walls of the tension member and curved above the journal boxes and below the web of the compression member.

24. A unitary cast truck frame having integral journal boxes at the ends thereof, said frame comprising a compression member and a tension member, each of channel form with the web of the channel on its upper side, said frame having end portions with relatively deep side walls into which the side walls of the tension and compression members merge and which are integrally joined to the journal boxes across the tops, the web of the tension member having a curved extension integral with the side walls above each journal box, each of said extensions lying between the web of the compression member and the top of the journal box.

25. A unitary cast truck frame having integral journal boxes at the ends thereof, said frame comprising a compression member and a tension member, each of channel form with the web of the channel on its upper side, said frame having end portions with relatively deep side walls into which the side walls of the tension and compression members merge and which are integrally joined to the journal boxes across the tops, the web of the tension member having a curved extension integral with the side walls above each journal box, each of said extensions lying between the web of the compression member and the top of a journal box, the side walls of said

tension member having inturned lower edges.

26. A unitary cast truck frame having integral journal boxes at the ends thereof, said frame comprising a compression member and a tension member, each of channel form with the web of the channel on its upper side, said frame having end portions with relatively deep side walls into which the side walls of the tension and compression members merge and which are integrally joined to the journal boxes across the tops, the web of the tension member having a curved extension integral with the side walls above each journal box, each of said extensions lying between the web of the compression member and the top of the journal box, said webs terminating short of the ends of the frame.

27. A truck frame having journal boxes at the ends thereof, top and bottom compression and tension members cast in one piece, end portions integral with the compression and tension members and extending across the tops of the journal boxes, said members being of channel form and said end portions having side walls into which the flanges of the compression and tension members merge, and a reinforcing web extending across the space between the side walls of each end portion, said reinforcing webs extending downwardly from the web of the compression member at an inclination thereto and having their ends disposed over said journal boxes and carried by the side walls of the compression member.

In testimony whereof I affix my signature.
MARK H. MARTIN.
